UNITED STATES PATENT OFFICE

2,550,973

DEVICE FOR CONDITIONING AND
RELOADING CARTRIDGE CASES

Lyle Shellman Corcoran, Hollywood, Calif.

Application February 23, 1949, Serial No. 77,917

1 Claim. (Cl. 86—24)

1

My invention relates to devices for conditioning used cartridge cases and for thereafter reloading the same. As is well known, many gunners prefer to condition and reload their own empty cartridge cases either for the purpose of economy or for the purpose of obtaining uniform loads and/or non-standard loads, or for other reasons.

With the foregoing in view, it is an object of my invention to provide an improved device for conditioning and reloading cartridge cases.

A further object is to provide an improved device for conditioning and reloading cartridge cases which is readily adapted for cartridge cases of various sizes.

A further object is to provide an improved cartridge case-conditioning and reloading device comprising a rigid base, a rigid slideway fixed to the base, a head fixed to the slideway in alignment with the base, means for mounting aligned cartridge case-conditioning and reloading tools on said head and/or on said base, a slide slidable on said slideway, and means for detachably mounting a cartridge case seat on said slide in alignment with said tools.

A further object is to provide in a device such as that last described improved means for reciprocating said slide on said slideway.

A further object is to provide in a device such as that last described a rock shaft journaled in the base and means operatively connecting the rock shaft to the slide for reciprocating the latter upon rocking of the shaft in opposite directions.

Other objects and advantages reside in the particular construction of the invention, combination and arrangement of the several parts thereof, and will be readily apparent to those skilled in the art upon reference to the attached drawings in connection with the following specification, wherein the invention is shown, described and claimed.

In the drawings:

Figure 1 is a side elevational view of the device according to the invention;

Figure 2 is a front view thereof, parts being broken away for clarity;

Figure 3 is a longitudinal vertical sectional view taken substantially on the plane of the line 3—3 of Figure 2;

Figure 4 is a horizontal sectional view taken substantially on the plane of the line 4—4 of Figure 3;

Figure 5 is a horizontal sectional view taken substantially on the planes of the line 5—5 of Figure 3;

Figure 6 is an enlarged fragmentary view similar to a portion of Figure 3, and showing a different form of reloading tool usable with the device.

2

Referring specifically to the drawings, wherein like reference characters have been used throughout the several views to designate like parts, 10 designates generally a base for the device which may be provided with a base flange 11 formed with vertical holes 12 therein to provide means for bolting the base to the table or other support. An upwardly-directed slideway 13 is rigidly connected to the base 10 in rearwardly-offset relation thereto. A head 14 is rigidly connected to the upper end of the slideway 13 and is formed with a forwardly-projecting portion 15 overhanging the forward portion of the base 10. In the embodiment illustrated, the base 10, slideway 13 and head 14 are formed of a single casting and the slideway comprises a vertical cylindrical post. Obviously, the same could assume other forms.

The overhanging portion 15 of the head 14 is formed with any suitable means for mounting a cartridge case-conditioning and/or reloading tool therein. Thus, in the embodiment illustrated the overhanging portion 15 is formed with a vertical socket 16 which is interiorly threaded for threadedly engaging the periphery of a cartridge case tool 17. The particular tool 17 illustrated includes a die portion 19 for shaping the exterior of the cartridge case 20. The upper end of the tool 17 may be threaded for engaging a further tool 23 which includes a portion 21 adapted to pass through the neck of the cartridge to reshape the same and a depending pin 22 adapted to punch the used primer out of the cartridge case. As best seen in Figure 6, instead of the tool 23, a die 24 may be threaded in the upper end of the tool 17 and includes means for properly seating a bullet 25 in a loaded cartridge case 20. Obviously, crimping tools or dies may likewise be included, or substituted for the tools 17, 23 and 24, aforesaid.

40 A slide 30, which may comprise a split collar, is vertically slidable on the slideway or post 13 and includes a forwardly-extending platform 29 formed with a vertically-disposed, internally-threaded socket 28 in vertical alignment with the 45 socket 16 of the head 14. A depending tubular stem 27 of a cartridge case seat 26 is threaded in the socket 28. The upper surface of the seat 26 is formed with a horizontally-disposed slideway 31 in which the ejector flange of the cartridge case is slidably received. Thus, the cartridge case 20 may be slid horizontally onto the seat into the slideway 31 and therein retained by the overhanging flanges 32 of the slideway. The cartridge is held against vertical displacement. By making the seat in the form of a socket, means now to be described may be utilized to insert a primer into the base of the cartridge case. Thus, the base 10 is formed with a vertically-disposed, interiorly-threaded socket 33 55 which is in vertical axial alignment with the 60

sockets 28 and 16. Any suitable primer-inserting tool 34 is threadedly mounted in the socket 33 whereby a primer 35 is held for insertion into the base of the cartridge case 20. As illustrated in broken lines, Figure 3, the primer 35 is inserted in the case 20 upon downward movement of the collar 30 after a preliminary upward movement has resulted in the pin 22 punching out the old primer. Vertical reciprocation of the slide 30 is accomplished by means now to be described.

Thus, the base 10 is formed with a transverse bore 35' in which is journaled a rock shaft 36. The forward portion of the bore is cut away, as at 37, so as to provide in effect a pair of spaced and aligned bearings for the rock shaft 36. The rock shaft 36 is formed with an axial bore 38 and with a pair of radially-directed aligned sockets 39 intersecting such bore. Also, the shaft is formed with third radially-directed socket 40 which is preferably angularly offset relative to the sockets 39 and which is in-between the same in the region of the cut-away portion 37. An operating handle 41 is seated in the socket 40 and is formed with a transverse hole 41' alignable with the bore 38 of the shaft 36. Likewise, a pair of bellcrank arms 42 are seatable in the sockets 39. Each bell-crank arm 42 is formed with a transverse hole 43 which is likewise alignable with the bore 38 of the shaft 36. A locking pin 44 is slideable in the bore 38 and extensible slidably through the holes 43 and 41', whereby to rigidly connect the bellcrank arms 42 and operating handle 41 to the shaft 36. Any suitable keys 45 are engageable with the free ends of the pin 44 to retain the same against longitudinal displacement relative to the shaft 36. Drag links 46 are pivoted to the free ends of the bellcrank arms 42 by any suitable pivots 48. The free ends of the drag links are pivoted by any suitable pin 47 to opposite sides of the collar 46.

It follows from the foregoing that rocking of the rock shaft 36 in a clockwise direction by the handle 41 will cause elevation of the bellcrank arms 42 and drag links 46, whereby to elevate the collar 30 and force the cartridge case 20 carried by the seat 26 up into the tool or die 17. Also, rotation of the shaft 36 in a counter-clockwise direction will lower the collar and seat to the broken line position of Figure 3.

By detachably connecting the cartridge seat 26 to the platform 29, and by providing sockets for the tools 17, 23 or 34 on the head and base, it is obvious that the device is readily adapted to a large variety of cartridge sizes. Thus, all that is required is to replace the seat 26 with a seat

suitable for the particular size of cartridge to be processed and similarly replace the tools 23 or 17 with suitable tools.

While I have shown and described what is now thought to be a preferred embodiment of the invention, it is to be understood that the same is susceptible of other forms and expressions. Consequently, I do not limit myself to the precise structure shown and described hereinabove except as hereinafter claimed.

I claim:

A cartridge case-conditioning and reloading device, comprising in combination; a base, head, and connecting cylindrical post, the base and head having laterally projecting portions disposed in general vertical alignment, said head and base being provided with means for rigidly and detachably mounting cartridge case-conditioning and reloading tools thereon; a rotatable collar vertically slidable on the post, said collar being formed with a radially-extending platform in vertical alignment with the projections of the base and head, said platform carrying means for rigidly and detachably mounting a cartridge case seat thereon in vertical alignment with said means of the head and base; a rock shaft journaled in the projection of said base transverse thereto; a pair of generally parallel bellcrank arms rigidly connected to opposite ends of said shaft with their sides in sliding registration with the respective sides of the base projection; and a pair of drag links pivotally connecting said bellcrank arms to opposite sides of said collar with their inner faces disposed in sliding registration with the platform thereof, whereby to provide means for reciprocating said collar on said post upon rocking of said shaft in opposite directions.

LYLE SHELLMAN CORCORAN.
